MACHINE FOR APPLYING PROTECTIVE
COATING TO PIPES

Wayne C. Hall, Alhambra, Calif.

Application January 16, 1950, Serial No. 138,876

21 Claims. (CL. 118—3)

1

This invention relates to apparatus for applying protective coating to pipes and is particularly directed to improvements in a pipe wrapping machine.

The principal object of this invention is to provide apparatus for continuous wrapping of pipes which progress axially through the machine so that no interruption occurs while a wrapped pipe is set aside and a bare pipe is fed serially into operative position.

Another object is to provide a device of this type for continuous wrapping of pipes which operates automatically to omit the protective coating adjacent the ends of the pipes.

Another object is to provide a pipe wrapping device employing a carriage having novel means for supporting the rearward end of one pipe and the forward end of another.

Another object is to provide a pipe wrapping device employing power driven roller units for supporting the pipe and moving it axially, one of the roller units being retractile to permit passage of the carriage.

Another object is to provide a pipe wrapping machine having roller units of this type, which units may be manipulated to change the angle of cant of the drive rollers and to change the spacing of the rollers to accommodate pipe of different sizes.

A further object is to provide a pipe wrapping machine having a carriage for the forward end of the wrapped pipe, which carriage is progressed at a slow axial rate while the wrapping takes place and at a faster rate to bring the wrapped pipe to a discharge position.

Other and more detailed objects and advantages will appear more fully hereinafter.

In the drawings:

Figure 1 is a perspective view showing details of a pipe wrapping machine embodying my invention.

Figure 2 is a side elevation partly broken away showing details of the mounting of the valve plate for shutting off coating material when desired.

Figure 3 is a fragmentary sectional view taken substantially on the lines 3—3 as shown in Figure 2.

Figure 4 is a plan view partly in section showing details of construction of the intermediate carriage.

Figure 5 is a sectional end view taken substantially on the lines 5—5 as shown in Figure 4.

Figure 6 is a sectional elevation taken substantially on the lines 6—6 as shown in Figure 5.

Figure 7 is a plan view partly broken away of the apparatus shown in Figure 1.

Figure 8 is a plan view showing details of one of the power driven roller units.

5 Figure 9 is a side elevation thereof partly broken away and partly in section.

Figure 10 is an end elevation of the power driven roller unit, certain parts being in section.

10 Figure 11 is a side elevation partly broken away showing details of the retractile roller unit assembly.

Figure 12 is a perspective view of the intermediate carriage.

15 Figure 13 is a perspective view of the power driven carriage for supporting the forward end of the pipe being wrapped.

Figure 14 is a sectional end elevation taken substantially on the lines 14—14 as viewed in

20 Figure 7.

Figures 15, 16 and 17 are side elevations of the pipe wrapping device shown in diagrammatic form and illustrating the sequence of operations as pipes are passed serially in an axial direction

25 through the coating and wrapping zone.

Figure 18 is a top plan view in diagrammatic form partly broken away showing the position of the parts when a bare pipe is moved axially into position for support by the intermediate carriage.

30 Figure 19 is a side elevation in diagrammatic form showing the parts in the same position as illustrated in Figure 18.

Referring to the drawings, pipe lengths are progressed serially in an axial direction from a supply rack 10 on which bare pipe is stored to a storage rack 11. This rack 11 comprises two spaced inclined supports which receive the ends of the wrapped pipe. A series of power driven

35 roller units 12 support each pipe length and serve to rotate the pipe and cause it to move axially. As a bare pipe 13 moves axially toward the coating and tarring zone generally designated 14, the forward end of the bare pipe rests on rollers provided on the intermediate carriage 15. The carriage 15 also has additional rollers supporting the

40 rearward end of the pipe 16 which is passing through the coating and wrapping zone 14. The forward end of the pipe 16 is supported on rollers provided on the power driven forward carriage 17. Parallel rails 18 extend in an axial direction and the carriages 15 and 17 roll on these rails.

45 It is highly desirable and often essential that a short length of each pipe adjacent its ends be left bare and free of coating material. This requirement is imposed by the manner of connecting the pipe lengths end to end in the field. Or-

50

55

dinarily, the joining operation is performed by welding, and coating material interferes with the welding operation. Accordingly, the practice is to coat each pipe for the major portion of its length with the ends thereof left uncoated. After the pipe lengths are welded together end to end in the field the bare regions adjacent each joint are coated in any preferred manner.

Molten tar is poured onto the pipe being wrapped in two parallel streams which are spaced axially of the pipe. As the carriage 15 is progressed along the rails 18 a valve plate 19 supported by the carriage 15 shuts off the flow of the tar streams in a manner so that no tar is deposited on the pipes 13 and 16 in the region immediately adjacent their abutting ends. The carriage 15 rolls across the tar pit and the valve plate 19 moves away from the orifices 20 and 21 from which the tar streams flow so that no interruption occurs as the coating operation is completed on one pipe and commenced on the next pipe.

Referring to the various features of construction of the device in more detail, the supply rack generally designated 10 may include parallel inclined supports 22 for bare pipes 23. Power operated transfer mechanism is provided for moving the pipes 23 from the rails to the power driven roller units 12. As shown in the drawings this transfer mechanism may include levers 24 pivoted to the rails 22 and operated by power cylinder assemblies 25. When the pipe has been transferred from the storage rack 10 to the power driven roller units 12 it is rotated by the roller units and fed axially toward the coating zone 14. As clearly shown in Figures 7 to 10 each of these roller units 12 includes a pair of rollers 26. Each of the rollers is fixed on a shaft 27 rotatably mounted in spaced bearings 28. The bearings 28 are fixed on a sliding support 29 which rests on the upper surface 30 of the head 31. The sliding support 29 is provided with aligned apertures through which the countershaft 32 extends. A worm pinion 33 is keyed for rotation with the drive shaft 32 but is free to move axially therewith. A key (not shown) carried by the worm pinion 33 slides in an elongated keyway 34 provided in the drive shaft 32. Means (not shown) are provided for preventing axial motion of the worm pinion 33 with respect to the sliding support 29. A worm wheel 37 fixed to the shaft 27 is driven from the worm pinion 33. The drive shaft 32 is rotatably supported in spaced bearings 35 carried on the head 31 and receives power through a pair of bevel gears 36 and 36^a. From this description it will be understood that rotation of the drive shaft 32 serves to rotate the drive rollers 26.

Means are provided on the head 31 for adjusting the spacing of the rollers 26, and as shown in the drawings this means includes an adjusting screw 38 having right-hand threads 39 on one end and left-hand threads 40 on the other. Each of the sliding supports 29 is provided with a downwardly extending internally threaded element 41 which threadedly engage the screw 38. One end of the screw 38 is provided with a squared head 42 to which a suitable wrench (not shown) may be applied for turning the screw relative to the head 31. Such movement of the screw serves to move the sliding supports 29 toward and away from each other since the threads 39 and 40 are of opposite lead. It will be apparent that the adjustment provided with the screw 38 enables the rollers

26 to be moved toward or away from each other to accommodate pipes of various diameters.

The head 31 is provided with a downwardly extending cylinder 43 having a flange 44 which is fixed to the head 31. The cylinder 43 is turnably mounted within a bore 45 provided on the base structure 46. The central vertical drive shaft 47 carries the bevel gear 36 on its upper end and is mounted in axially spaced bearings 48 and 49 mounted on the cylinder 43 and head 31 respectively. A bevel gear 50 is fixed on the lower end of the shaft 47 and meshes with a companion bevel gear 51 which is fixed on the jack shaft 52. As shown clearly in Figure 7, the jack shaft 52 extends under a plurality of power driven roller units 12 and receives power from motor 53 operating through a drive chain 54. Bearings 55 are provided on each of the bases 46 for supporting the jack shaft 52.

The swivel mounting of the head 31 on the base 46 in each of the power driven roller units 12 enables the drive rollers 26 to be canted at any desirable degree for effecting axial movement of the rotating pipe supported and driven by the rollers. Since the vertical shaft 47 is positioned on the axis of the cylinder 43 the head 31 can be swung at any desired position for canting the rollers without interfering with the power drive for rotating the rollers. Means are provided for shifting each of the heads 31 simultaneously, and as shown in the drawings this means includes a control rod 56 having a plurality of clevises 57 fixed thereto. A link 58 pivotally connects each clevis to a pair of ears 59 provided on each head 31. The control rod 56 is slidably mounted on a framework 60 and its position may be adjusted lengthwise by means of a hand wheel 61 having internal threads which engage the threaded end 62 of the rod 56. The hand wheel is confined between thrust elements 63 provided on the frame 60. When the hand wheel 61 is turned each of the heads 31 of the power driven roller assemblies is shifted so that the drive rollers may be simultaneously canted at any desired position. It will be understood that the greater the angle of cant the faster the pipe is fed axially for the same speed of rotation.

The power driven roller unit 64 which is adjacent the coating and wrapping zone 14 is arranged to be retracted when necessary to permit the intermediate carriage 15 to pass by along the rails 18. This power driven roller unit 64 is provided with a swivel head 65. The power driven rollers 26 on this head are substantially the same as those described in connection with the power driven roller units 12, and they are driven in substantially the same manner. A screw 38 is provided for adjusting the rollers 26 toward and away from each other as described above. The head 65 is mounted for turning movement relative to a supporting piston 66 and a link 67 connects the head 65 with the next adjacent power driven roller unit 12 so that the head 65 is shifted simultaneously with the heads 31 whenever the hand wheel 61 is turned. The piston 66 is received within a cylinder 68 and an air pipe 69 communicates with the lower end of the cylinder so that the piston 66 may be raised and lowered. A slot 70 formed in the side of the piston 66 provides clearance for the horizontal shaft 71 which drives the vertical shaft 71 through a pair of bevel gears 72 and 73. The bevel gear 72 is keyed for rotation with the shaft 71 but is free to slide axially with respect thereto. A chain 74 enables the shaft 70 to be driven

from the jack shaft 52. When air pressure is supplied to the pipe 68, the piston 66 is elevated to bring the rollers 26 into the operative position shown in Figure 11. When the air pressure is exhausted from the lower end of the cylinder 67, the piston 66 and power driven roller unit 64 descend by gravity to an inoperative position as shown in Figure 1, and in this retracted inoperative position the intermediate carriage 15 may roll freely along the rails 18 unobstructed by the unit 64.

The coating and wrapping zone generally designated 14 may take any preferred or desirable form and any suitable coating substances and wrappings may be applied as desired. For purposes of illustration I have shown two axially spaced tar streams 75 and 76 which issue from the orifices provided in the ends of the heated reservoirs 77 and 78 respectively. The first stream 75 of hot tar falls on the bare pipe and a continuous strip of suitable material, such as, for example, cellophane 79 is applied over the first coating of tar. The second tar stream 76 descends on the cellophane wrapping and is itself covered by another suitable wrapping, for example, a continuous strip of tar paper 80. The cellophane 79 and tar paper 80 are supplied from suitable coils or drums (not shown) and are caused to be wrapped spirally on the pipe as the pipe is turned and progressed axially. A tar pit 81 is positioned to receive excess tar from the streams 75 and 76, and suitable guards 82 may be provided at the sides of the pit to prevent splashing of tar upon operators of the machine. Tar reaching the pit 81 is recirculated to the heated reservoirs 77 and 78 by means of a suitable pump 83 and piping connections 84.

The intermediate carriage 15 is provided with a frame having a pair of parallel longitudinal members 85 joined by cross-members 86. Each of the longitudinal members is provided with a pair of flanged wheels 87 which roll on the rails 18. Sliding blocks 88 and 89 are mounted for transverse movement on the cross-members 86 and each of these blocks carries a pair of idler rollers 90 and 91 respectively. As shown clearly in Figure 4 the rollers 90 and 91 are not parallel, but on the contrary are mounted at an angle with respect to a plane normal to the pipe axis. The rollers 90 are connected by a universal joint 92 so that they rotate at the same speed. Similarly, the rollers 91 are connected by a universal joint 93 so that they rotate at the same speed. A disk 94 is mounted on the universal joint 93 and is positioned centrally between the rollers 91. This disk rotates in a plane normal to the pipe axis.

Means are provided for moving the rollers 91 toward and away from the rollers 90, and as shown in the drawings this means includes a pair of screw elements 95 and 96, each of which is provided with a right-hand threaded portion 97 and a left-hand threaded portion 98. One end of each of these screw elements projects through one of the parallel longitudinal members 85, and the projecting end is squared as shown at 99 to receive a wrench (not shown). The other ends of the elements 95 and 96 project through the other longitudinal member 85 and are provided with sprockets 100 and 101 connected by a chain 102. Each of the sliding blocks 88 and 89 is provided with two pairs of nuts 103 which are restrained from rotation and are anchored with respect to the blocks. These nuts receive the threaded portions of the screw elements 95 and 96 so that rotation of the screw elements moves

the blocks 88 and 89 toward and away from each other. The purpose in this adjustment is to enable the rollers 90 and 91 to accommodate pipe of various sizes. The mounting for the rollers 90 and 91 may include fluid containing recesses 88^a into which the rollers dip as they turn. The fluid, for example, water, keeps the rollers cool and prevents undesirable adhesion of tar to the roller surface.

10 The intermediate carriage 15 supports the forward end of the bare pipe and the rearward end of the pipe being wrapped as the pipes and carriage 15 move axially toward the coating and wrapping zone 14. As the carriage 15 approaches the first tar stream 75 the valve plate 19 enters the channel 104 preparatory to cutting off the flow of tar from the orifice 20. The valve plate 19 is supported on the carriage 15 by means of a pair of upright posts 105 which are welded or otherwise secured to the sliding block 89. The valve plate 19 is connected by means of pins 106 to clevises 107 carried on the extending ends of rods 108. The rods extend through compression springs 109 which are confined between the clevises 107 and a guide carrier 110. The rods 108 extend through suitable openings in the guide carrier 110 and are provided with stop pins 111 at their projecting ends to limit the travel of the rods under influence of the springs 109. The guide carrier 110 is supported on the upright posts 105 by means of hinged brackets 112 which are connected by hinge pins 113 to the bracket 114. This bracket is provided with spaced apertures 115 for reception of the posts 105. Set screws 116 are provided for clamping the guide carrier 110 with respect to the hinged brackets 112. The construction just described permits the valve plate 19 to press resiliently into the channel 14 for effective shut-off of the flow of tar when desired, and also enables the assembly including the valve plate 19, rods 108, and guide carrier 110 to be pivoted about the pivot pins 113 to tilt the assembly to an inoperative position on return movement of the carriage 15 to prevent entrance of the valve plate 19 into the channel 104.

40 The nonparallel positioning of the rollers 90 and 91 as shown in Figure 4 serves to cause the adjacent ends of the pipes 13 and 16 to move toward each other and to abut against the separating disk 94. The pipes 13 and 16 are in this way maintained against separation as the intermediate carriage 15 rolls along the rails 18. The rollers 90 and 91 on one side of the separator disk 94 are canted in one direction, while the rollers 90 and 91 on the other side of the separator disk 94 are canted in the other direction.

50 The power driven leading carriage 17 supports the forward end of the forward pipe and supplies power for rotating it. As best shown in Figure 13 this leading carriage 17 is provided with power driven flanged wheels 114^a and idler wheels 115 rolling on the rails 18. A motor 116 driving through a change-speed belt transmission 117 turns a power shaft 118. This shaft 118 drives the rollers 114^a through the shaft 119 by way of chain 120, and this shaft 118 also drives the jack shaft 121 through chain 122. Worm pinions 123 fixed on the jack shaft 121 drive worm wheels 124 fixed on shafts 125 and 126 respectively. The shaft 125 carries the driving roller 127 and the shaft 126 carries the driving roller 128. The shafts 125 and 126 are each carried on a sliding block assembly so that the rollers 127 and 128 may be moved toward and away from each other.

As shown in the drawings, a screw element 129 having a right-hand and left-hand threaded portion cooperates with nuts on the sliding blocks for adjusting the transverse spacing of the rollers 127 and 128. A disk 130 is fixed on the shaft 126 and is adapted to contact the leading end of the forward pipe. Power supplied by the motor 116 serves to move the carriage 17 forward along the rails 18 as well as to supply power for rotating the drive rollers 127 and 128. The speed of the motor may be controlled so that the carriage 17 moves forward at a relatively slow rate while the pipe is being wrapped and then moves at a faster rate to bring the pipe adjacent the storage rack 11 after the wrapping operation upon that pipe length is complete. The motor 16 is reversible so that the leading carriage 17 may be returned along the rails to support the forward end of the next pipe which is passing through the coating and wrapping zone 14.

Means are provided for ejecting a completely wrapped pipe from its supported position on the carriages 17 and 15 onto the storage rack 11. As shown in the drawings this means includes a lever 131 pivoted to the leading carriage 17 by means of the pin 132. An air cylinder 133 mounted on the carriage 17 has a projecting rod 134 which may be extended to lift the end 135 of the lever 131. Such movement of the lever causes the pipe to be raised off the rollers 127 and 128 so that it may roll laterally along the lever 131 to the storage rack 11. A similar pivoted lever 136 is provided on the intermediate carriage 15 and is connected thereto by means of the pivot pin 137. Power for lifting the lever 136 is supplied by a power cylinder 138 carried on a frame 139 below the rails 18. When the intermediate carriage 15 rolls to a position above the location of the power cylinder 138, air pressure is supplied which causes the piston rod 140 to be extended and raise the sliding plate 141 into contact with the underside of the lever 136, thereby elevating it so that the pipe is raised clear of the rollers 90 and 91 and allowing the pipe to roll along the inclined lever onto the storage rack 11.

The operation of the pipe wrapping machine is shown diagrammatically in Figures 15 to 19. The bare pipe 13 is rotated and caused to move axially forward by means of the power driven roller units 12. The forward end of the bare pipe 13 is carried on the rollers of the intermediate carriage 15 and abuts the separator disk 94. The rearward end of the pipe 16 being wrapped also rests on the rollers of the intermediate carriage 15 and abuts the separator disk 94. The forward end of the pipe 16 rests on the forward carriage 17. The rollers of the forward carriage 17 rotate the pipe 16 and the forward carriage 17 is driven along the rails 18 so that the pipe 16 moves forward at the same speed as the pipe 13. The coating and wrapping operation proceeds as the pipes 13 and 16 turn and move axially along the rails 18. The valve plate 19 stops the flow of the tar stream 75 just before the tar stream reaches the rearward end of the pipe 16, and therefore the rearward end remains bare. The valve plate 19 shuts off the tar stream 75 until the forward end of the pipe 13 has passed under the reservoir 77. As the plate 19 moves along with the intermediate carriage 15 the tar stream 75 is again permitted to flow so that the pipe 13 is coated with tar from a point spaced axially from the forward end thereof. The same action takes place whereby the valve plate 19 shuts off the flow of the tar stream 76 so that no tar is de-

posited adjacent the ends of the pipes 16 and 13. The wrapping operation continues uninterrupted until two strips 79 and 80 sequentially reach the position of the separator disk 94 which has a sharpened edge. The wrapping strips are each cut at such time and are re-applied manually to the pipe 13 as soon as the carriage 15 has passed beyond the region of application of the wrapping strips. The rotation and axial movement of the pipe, however, continues uninterrupted.

When the carriage 15 passes beyond the position at which the second wrapping strip 80 is applied the retractile roller head 64 is elevated to form a support for the pipe 13. The leading carriage 17 is then speeded up in its movement along the rails 18 so that the wrapped pipe 16 moves away from the pipe 13 until its ends are opposite the storage racks 11. The power cylinders 138 and 133 are then energized to raise the pivoted levers 136 and 131 respectively to lift the pipe 16 off the supporting rollers and permit it to roll laterally onto the storage racks 11. While the pipe 16 is being transported at a relatively fast rate along the rails 18 to the position of the storage rack, and while it is being ejected from the carriages 15 and 17, the pipe 13 continues its uniform rotation and axial movement imparted by the power operated roller units 12 and 64. The coating and wrapping operation proceeds on the forward end of the pipe 13 while the pipe 16 is being discharged onto the storage rack.

When the pipe 16 has been transferred to the storage rack the carriage 15 is pushed manually back along the rails 18 to a position over the tar pit 81. The plate 19 is swung upwardly to an inoperative position about the hinge pins 113 so that neither of the tar streams 75 or 76 is interrupted. The power driven leading carriage 17 is returned along the rails 18 under power to position the rollers thereon under the forward end of the pipe 13. If necessary the power driven roller head 64 can be elevated slightly so that the forward end of the pipe 13 clears the drive rollers on the carriage 17. The forward end of the pipe 13 strikes the disk 130 and the head 64 is then lowered so that the pipe rests on the rollers 127, 128. The motor 116 on the carriage 17 is then operated to cause the carriage 17 to move to the right while the rollers 127 and 128 assist in rotating the pipe 13. The head 64 is then retracted to the inoperative position shown in Figure 15. The rollers 90 and 91 on the intermediate carriage 15 are then moved away from each other by turning one of the screw elements 95 or 96. The intermediate carriage 15 is then rolled to the left against the stop 142 at the end of the rails 18. The rollers 90 and 91 in their widely spaced positions do not contact the pipe and hence clearance is provided so that the carriage 15 rolls without contacting the pipe or the wrapping materials. It will be understood that during the interval of transferring the wrapped pipe 16 to the storage rack and return of the carriages 15 and 17, the pipe 13 continues its rotation and axial movement while the tar streams 75 and 76 are deposited thereon and while the strips 79 and 80 are wrapped around it.

When the intermediate carriage 15 has been moved to the left of the retractile power driven roller unit 64 as viewed in Figure 17, the unit 64 is again elevated to support the pipe and to assist in rotating it and moving it axially. When the rearward end of the pipe 13 approaches the

position shown in Figure 18 the rollers 90 and 91 on the intermediate carriage 15 are moved toward each other to bring them into contact with the pipe 13. At the same time the separator disk 94 is moved between the abutting ends of the pipe 13 and the following pipe 13a. When the rearward end of the pipe 13 is supported by the carriage rollers 90 and 91 the power driven head 64 is retracted so that the carriage then rolls along the rails 18 toward the tar pit 81. The sequence of operations is then repeated.

From the above description it will be understood that the bare pipe is first rotated by the power driven roller units 12, and then by the units 12 and the unit 64. When the forward end of the pipe is rested on the rollers of the leading carriage 17 the rotation is effected by the power driven rollers on the carriage 17 and by the power driven rollers on the units 12 and 64. When the rearward end of the pipe is carried on the intermediate carriage 15 the power driven rollers 127 and 128 on the leading carriage 17 supply all of the power for turning the pipe and for progressing it axially. Bare lengths of pipe are fed serially into position from the supply rack 10 at regular intervals and the power driven roller units 12 advance the pipe continuously without interruption. Coated pipe lengths with the ends bare and uncoated are deposited at regular intervals on the storage rack 11, but the coating and wrapping process is uninterrupted while bare pipe lengths are added and coated pipe lengths are withdrawn.

Having fully described my invention, it is to be understood that I do not wish to be limited to the details herein set forth, but my invention is of the full scope of the appended claims.

I claim:

1. In a pipe wrapping machine, the combination of: roller means operating to support and rotate a pipe and to progress it in an axial direction, means positioned at a fixed location along the path of axial movement of the pipe for applying a protective coating to the pipe as it moves axially, said roller means being operable continuously to progress pipes at a uniform rate serially in end-to-end relation past said coating means, axially movable carriage means for rotatably supporting a pipe while it is being coated, means for moving the carriage means at a rate faster than said uniform rate to move a coated pipe away from a following pipe being coated, and without varying the uniform rate of axial movement of the following pipe.

2. In a pipe wrapping machine, the combination of: a plurality of power driven roller units cooperating to support and rotate a pipe and to progress it in an axial direction, means positioned at a fixed location along the path of axial movement of the pipe for applying a protective coating to the pipe as it moves axially, said roller units being operable continuously to progress pipes at a uniform rate serially in end-to-end relation past said coating means, axially movable carriage means for rotatably supporting a pipe while it is being coated, means for moving the carriage means at a rate faster than said uniform rate to move a coated pipe away from a following pipe being coated, and without varying the uniform rate of axial movement of the following pipe.

3. In a pipe wrapping machine, the combination of: roller means operating to support and rotate a pipe and to progress it in an axial direc-

tion, means positioned at a fixed location along the path of axial movement of the pipe for applying a protective coating to the pipe as it moves axially, said roller means being operable continuously to progress pipes at a uniform rate serially in end-to-end relation past said coating means, axially movable carriage means for rotatably supporting a pipe while it is being coated, shut-off means supported by the carriage means for arresting operation of the coating means when adjacent ends of a leading and following pipe pass thereby, means for moving the carriage means at a rate faster than said uniform rate to move the coated pipe away from the following pipe being coated, and without varying the uniform rate of axial movement of the following pipe.

4. In a pipe wrapping machine, the combination of: a plurality of power driven roller units cooperating to support and rotate a pipe and to progress it in an axial direction, means positioned at a fixed location along the path of axial movement of the pipe for applying a protective coating to the pipe as it moves axially, said roller units being operable continuously to progress pipes at a uniform rate serially in end-to-end relation past said coating means, axially movable carriage means for rotatably supporting a pipe while it is being coated, shut-off means supported by the carriage means for arresting operation of the coating means when adjacent ends of a leading and following pipe pass thereby, means for moving the carriage means at a rate faster than said uniform rate to move the coated pipe away from the following pipe being coated, and without varying the uniform rate of axial movement of the following pipe.

5. In a pipe wrapping machine, the combination of: roller means operating to support and rotate a pipe and to progress it in an axial direction, means positioned at a fixed location along the path of axial movement of the pipe for applying a protective coating to the pipe as it moves axially, said roller means being operable continuously to progress pipes at a uniform rate serially in end-to-end relation past said coating means, axially movable carriage means for rotatably supporting a pipe while it is being coated, the carriage means including a carriage rotatably supporting the rearward end of a leading pipe and the forward end of a following pipe, shut-off means on the carriage for arresting operation of the coating means when the carriage passes the coating means, means for moving the carriage means at a rate faster than said uniform rate to move the leading pipe away from the following pipe, and without varying the uniform rate of axial movement of the following pipe.

6. In a pipe wrapping machine, the combination of: roller means operating to support and rotate a pipe and to progress it in an axial direction, rails extending axially of the pipe, means positioned at a fixed location along the path of axial movement of the pipe for applying a protective coating to the pipe as it moves axially, said roller means being operable continuously to progress pipes at a uniform rate serially in end-to-end relation past said coating means, axially movable carriages on the rails for rotatably supporting a pipe while it is being coated, one of the carriages rotatably supporting the forward end of a leading pipe, another carriage rotatably supporting the rearward end of the leading pipe and the forward end of a following pipe, shut-off means on the second mentioned carriage for ar-

11

resting operation of the coating means when adjacent ends of the leading and following pipes pass the coating means, the carriages being movable along the rails when desired at a rate faster than said uniform rate to move the coated pipe away from the following pipe, and without varying the uniform rate of axial movement of the following pipe.

7. In a pipe wrapping machine, the combination of: a plurality of power driven roller units 10 cooperating to support and rotate a pipe and to progress it in an axial direction, rails extending axially of the pipe, a leading carriage movable along the rails and provided with rollers for supporting the forward end of a leading pipe, an intermediate carriage movable along said rails and having a first pair of rollers for supporting the rearward end of said leading pipe and a second pair of rollers for supporting the leading end of a following pipe, means positioned at a fixed location with respect to said rails for applying a protective coating to the pipes as they move axially, and means on the intermediate carriage for interrupting the action of the coating means when the intermediate carriage passes the location of the coating means whereby a short length of each pipe adjacent the abutting ends remains uncoated.

8. In a pipe wrapping machine, the combination of: a plurality of power driven roller units 20 cooperating to support and rotate a pipe and to progress it in an axial direction, rails extending axially of the pipe, a leading carriage movable along the rails and provided with power driven rollers for supporting the forward end of a leading pipe and for rotating it, an intermediate carriage movable along said rails and having a first pair of idler rollers for supporting the rearward end of said leading pipe and a second pair of idler rollers for supporting the leading end of a following pipe, means positioned at a fixed location with respect to said rails for applying a protective coating to the pipes as they move axially, and means on the intermediate carriage for interrupting the action of the coating means when the intermediate carriage passes the location of the coating means whereby a short length of each pipe adjacent the abutting ends remains uncoated.

9. In a pipe wrapping machine, the combination of: a plurality of power driven roller units 30 cooperating to support and rotate a pipe and to progress it in an axial direction, rails extending axially of the pipe, a leading carriage movable along the rails and provided with power driven rollers for supporting the forward end of a leading pipe and for rotating it, an intermediate carriage movable along said rails and having a first pair of rollers for supporting the rearward end of said leading pipe and a second pair of rollers for supporting the leading end of a following pipe, the first and second pairs of rollers being connected for rotation as a unit, and means positioned at a fixed location with respect to said rails for applying a protective coating to the pipes as they move axially.

10. In a pipe wrapping machine, the combination of: a plurality of power driven roller units 40 cooperating to support and rotate a pipe and to progress it in an axial direction, rails extending axially of the pipe, a leading carriage movable along the rails and provided with rollers for supporting the forward end of a leading pipe, an intermediate carriage movable along

12

said rails and having a first pair of rollers for supporting the rearward end of said leading pipe and a second pair of rollers for supporting the leading end of a following pipe, and means positioned at a fixed location with respect to said rails for applying a protective coating to the pipes as they move axially.

11. In a pipe wrapping machine, the combination of: a plurality of power driven roller units 50 cooperating to support and rotate a pipe and to progress it in an axial direction, a carriage supported to move axially and having supporting rollers contacting the pipe near the leading end thereof, the carriage having additional supporting rollers for contacting another pipe near the rearward end thereof, the supporting rollers on the carriage for each of the pipes connected for dependent rotation and being canted so that the adjacent ends of the pipes tend to move toward each other, and a separator disk rotatably supported on the carriage contacted by the said adjacent ends of the pipes.

12. In a carriage for a pipe wrapping machine, the combination of: a frame supported to move 25 axially and having a pair of supporting rollers for contacting a leading pipe near the rearward end thereof, the frame having an additional pair of supporting rollers for contacting a following pipe near the forward end thereof, the supporting rollers on the carriage for each of the pipes being canted so that the adjacent ends of the pipes tend to move toward each other when the pipes are rotated in the same direction, and a separator disk rotatably supported 30 on the carriage for engagement by the adjacent ends of the pipes.

13. In a carriage for a pipe wrapping machine, the combination of: a frame supported to move 40 axially and having a pair of supporting rollers for contacting a leading pipe near the rearward end thereof, the frame having an additional pair of supporting rollers for contacting a following pipe near the leading end thereof, the supporting rollers on the carriage for each of the pipes 45 being canted so that the adjacent ends of the pipes tend to move toward each other, means including a universal joint connecting one roller of each pair for dependent rotation, means including a second universal joint for connecting the other roller of each pair for dependent rotation, and a separator disk rotatably supported on the carriage for engagement by the adjacent ends of the pipes.

14. In a carriage for a pipe wrapping machine, the combination of: a frame supported to move 55 axially and having a pair of supporting rollers for contacting a leading pipe near the rearward end thereof, the frame having an additional pair of supporting rollers for contacting a following pipe near the leading end thereof, the supporting rollers on the carriage for each of the pipes being canted so that the adjacent ends of the pipes tend 60 to move toward each other, means including a universal joint connecting one roller of each pair for dependent rotation, means including a second universal joint for connecting the other roller of each pair for dependent rotation, and a separator disk mounted on one of said universal joints for engagement by the adjacent ends of the pipes.

15. In a pipe wrapping machine, the combination of: an axially movable leading carriage for 70 rotatably supporting the forward end of a leading pipe, an axially movable intermediate carriage having supporting rollers for contacting a coaxial following pipe near the leading end thereof,

13

the intermediate carriage having additional supporting rollers for contacting the leading pipe near the rearward end thereof, a plurality of power driven roller units cooperating to support and rotate the following pipe and to progress it in an axial direction, the supporting rollers on the intermediate carriage for each of the pipes being canted so that the adjacent ends of the pipes tend to move toward each other when the pipes are rotated in the same direction, and a separator disk rotatably supported on the intermediate carriage for engagement by the said adjacent ends of the pipes.

16. In a pipe wrapping machine, the combination of: an axially movable leading carriage for rotatably supporting the forward end of a leading pipe, an axially movable intermediate carriage having supporting rollers for contacting a co-axial following pipe near the leading end thereof, the intermediate carriage having additional supporting rollers for contacting the leading pipe near the rearward end thereof, a plurality of power driven roller units cooperating to support and rotate the following pipe and to progress it in an axial direction, the supporting rollers on the intermediate carriage for each of the pipes being canted so that the adjacent ends of the pipes tend to move toward each other, said supporting rollers being operatively connected for dependent rotation, and a separator disk rotatably supported on the intermediate carriage for engagement by the said adjacent ends of the pipes.

17. In a pipe wrapping machine, the combination of: a plurality of power driven roller units cooperating to support and rotate a pipe and to progress it in an axial direction, each of the roller units including a head supported on a base, a pair of laterally spaced pipe contacting rollers rotatably mounted on the head, drive means for turning said rollers, including a power shaft extending radially of the pipe, swivel means connecting the head and base so that the head may swivel about the axis of said drive shaft, and linkage means connecting the heads for dependent swiveling movement.

18. In a pipe wrapping machine, the combination of: a plurality of power driven roller units cooperating to support and rotate a pipe and to progress it in an axial direction, each of the roller units including a head supported on a base, a pair of laterally spaced pipe contacting rollers rotatably mounted on the head, drive means for turning said rollers, including a power shaft extending radially of the pipe, swivel means connecting the head and base so that the head may swivel about the axis of said drive shaft, and means including linkage means connecting the heads for simultaneously swiveling each of the heads relative to its respective base.

19. In a pipe wrapping machine, the combination of: a plurality of power driven roller units cooperating to support and rotate a pipe and to progress it in an axial direction, means positioned

14

at a fixed location along the path of axial movement of the pipe for applying a protective coating to the pipe as it moves axially, said roller units being operable continuously to progress pipes at a uniform rate serially in end-to-end relation past said coating means, axially movable carriage means for rotatably supporting a pipe while it is being coated, means for retracting one of the roller units away from pipe engaging position to provide clearance permitting the carriage means to operate on either side of said roller unit.

20. In a pipe wrapping machine, the combination of: a plurality of power driven roller units cooperating to support and rotate a pipe and to progress it in an axial direction, means positioned at a fixed location along the path of axial movement of the pipe for applying a protective coating to the pipe as it moves axially, said roller units being operable continuously to progress pipes at a uniform rate serially in end-to-end relation past said coating means, an axially movable carriage for rotatably supporting the forward end of a pipe, a roller support for the pipe positioned at a fixed location between the coating means and the power driven roller units, and means for retracting said roller support from operative position to provide clearance permitting the carriage to move axially on either side of the roller support.

21. In a pipe wrapping machine, the combination of: a plurality of power driven roller units cooperating to support and rotate a pipe and to progress it in an axial direction, rails extending axially of the pipe, a leading carriage movable along the rails and provided with rollers for supporting the forward end of a leading pipe, an intermediate carriage movable along said rails and having a first pair of rollers for supporting the rearward end of said leading pipe and a second pair of rollers for supporting the leading end of a following pipe, means positioned at a fixed location with respect to said rails for applying a protective coating to the pipes as they move axially, a roller support for the pipes positioned at a fixed location between the rails and between the coating means and the power driven roller units, and means for retracting said roller support from operative position to provide clearance permitting the intermediate carriage to move on the rails on either side of the roller support.
